UNITED STATES PATENT OFFICE

WILLIAM J. KIRK, OF WELLSBURG, WEST VIRGINIA

DILATOR

Application filed May 15, 1926. Serial No. 109,280.

My invention relates to dilators, and particularly those of the kind adapted for use with rectal diseases or trouble. It has in view to provide, in one instrument or implement, a hollow body portion for insertion and massage manipulation, also for application of medication, and for heating, when desired, as hereinafter more fully described.

In the drawings showing certain preferred 10 embodiments of the invention:

Fig. 1 is a view of the device in elevation;

Fig. 2 is a central longitudinal sectional view with the plunger and handle extended;

Fig. 3 is a similar view with the plunger 15 screwed in to the limit of its movement;

Fig. 4 is a similar view, showing the plunger provided with a heating element;

Fig. 5 is a cross section on the line V, V, 20 of Fig. 1;

Fig. 6 is a sectional detail view showing the closing plug for use with a chemical heater.

The body of the dilator consists of a hollow tubular member 2 having a tapered insertion point 3, with the wall of the main body 25 somewhat undulating as shown. The insertion point 3 is of a non-bulging diameter, substantially the same as the minimum diameter of member 2, and tapered forwardly beyond the next adjacent outward annular undula-

30 tion, as shown.

The hollow terminal portion is adapted to contain a charge 4 of medicated substance for exudation through laterally arranged perforations 5 by internal pressure on the medication 4.

Such pressure is effected by a plunger 6 forming the inner end of a hollow stem 7 which is screwed into the outer threaded end 40 portion of body 2 by a threaded neck 8. The cooperating threads are of sufficient length to provide for ample plunger adjustment and forcing of the medication for several treatments.

45 Outwardly beyond the threaded portion 8, stem 7 is provided with a flared finger grasping terminal 9 of trumpet formation, enabling the user to take a firm hold thereof, either for manipulation of the dilator as a whole for annular or longitudinal movement, 50 as in massaging, or for relative movement of

the plunger within the hollow body portion.

Terminal 9 also constitutes a thimble shaped socket *a* for insertion of the finger of the user or operator, thus facilitating easy manipulation of the dilator, without necessitating grasping of it outwardly. In such construction the plug 17 may be set inwardly of the outer end of the finger terminal 9 as shown in Fig. 6, leaving the open tapered space *a* for the finger as in the principal figures.

The body portion is also provided with an annular rounded edge ring 10 having a front flat annular face at right angles to the longitudinal center of the dilator. Ring 10 in 65 such form provides a limiting abutment, and reinforces the device as clearly shown.

When it is desired to include heating with the implement, a suitable heater 11, of the well known electrical resistance type, is inserted in the hollow interior 12 of stem 7 and connected by current supply wires 13 to any source of current. In such construction the wires are preferably extended through an outer holding plug 14 screwed as at 15 into the 70 flaring grasping terminal 9, with a separate connecting element 16, the device otherwise being substantially the same as above described.

I may also utilize any suitable chemical 80 heating substance or material instead of the electrical heater, by merely enclosing it within the hollow plunger by the endmost plug 17, of suitable tight construction.

With either construction the implement is 85 capable of merely mechanical use alone, for dilation or massage, without medication or without heat application. It is capable of use in the same general manner as dilators 90 and for the same purpose, while providing by its construction an easily handled and effective manipulator and expander.

When used with medication, the filling charge 4 may be exuded to any desired degree by manipulation of the holding terminal 95 to force the plunger 6 inwardly to any desired extent.

In the same way the device may be used 100 either with or without medication, but with

the application of internal heat, as provided for in the construction of Fig. 4.

The time of use or of application of medication, or heat, is easily within the control 5 of the operator, and the various uses for treatment of different diseases or troubles is entirely within the province of the operator. The application of medication may be located at any desired point merely by regulating the 10 degree of insertion followed by adjustment of the plunger.

The construction and operation of the device will be readily understood and appreciated by all those familiar with this class of 15 articles. It may be made of various sizes and capacity as to reservoir content or otherwise changed or varied by the skilled mechanic. It will be understood also that while the device is preferably made of hard rubber 20 or bakelite, it may be made of metal or other suitable material, but all such or other changes are to be considered as within the scope of the following claims.

What I claim is:

- 25 1. A dilator consisting of a hollow elongated integral body circular in cross section having a non-bulging tapered perforated minimum diameter end portion and a longitudinally undulating variable and maximum 30 diameter exterior and a rear annular flat faced limiting flange, and a continuously integral interior hollow plunger having threaded connection with the outer end of the body.
- 35 2. A dilator consisting of a hollow elongated integral body circular in cross section having a non-bulging tapered perforated forward end portion, a longitudinally undulating variable diameter middle exterior and a rear annular limiting ring having a flat front 40 face at right angles to the longitudinal center of the dilator, a continuously integral interior plunger having threaded connection with the outer end of the body, and an outermost extended interiorly tapered flaring 45 trumpet shaped grasping terminal.
- 50 3. A dilator consisting of a hollow elongated integral body circular in cross section having a tapered perforated end portion and a longitudinally undulating variable diameter exterior, and a continuously integral interior hollow plunger having threaded connection with the outer end of the body and provided at its inner end with a closed piston 55 like terminal and at its outer end with an extended flaring interiorly tapered trumpet shaped grasping terminal.
- 60 4. A dilator consisting of a hollow elongated integral body circular in cross section having a tapered perforated end portion and a longitudinally undulating variable diameter exterior, a continuously integral interior hollow plunger having threaded connection with the outer end of the body and provided 65 at its inner end with a closed piston like termi-

nal and at its outer end with an extended flaring trumpet shaped grasping terminal, a heater in the hollow plunger, and a plug having threaded engagement within the flaring grasping terminal providing a support for 70 current supply conductors leading to the heater.

5. A dilator consisting of a hollow elongated integral body circular in cross section having a tapered perforated end portion and a longitudinally undulating variable diameter exterior, a continuously integral interior hollow plunger having threaded connection with the outer end of the body and provided at its inner end with a closed piston like terminal and at its outer end with an extended flaring interiorly tapered trumpet shaped grasping terminal, and a plug tightly secured within the flaring grasping terminal and closing the interior of the hollow plunger. 75

6. In a dilator of the class described, the combination of a hollow elongated integral body circular in cross section having an interiorly and exteriorly tapered end provided with a terminal and lateral perforations, and exudable substance within the tapered end, an outer annular rounded flat faced limiting collar and interior threads at the inside of the other end of the hollow body, and a hollow plunger having an outer flaring grasping terminal in threaded engagement with said threads and provided with an inner piston terminal adapted to force the exudable substance through said perforations. 80

In testimony whereof I hereunto affix my 100 signature.

WILLIAM J. KIRK.
